DESIGN FOR A COMBINED WATER CLOSET BOWL AND FOOT REST

Perry F. Stromblad, Clairton, Pa.

Application October 27, 1941, Serial No. 103,910

Term of patent 7 years

To all whom it may concern:

Be it known that I, Perry F. Stromblad, a subject of the King of Sweden, residing at Clairton, in the county of Allegheny and State of Pennsylvania, have invented a new, original, and ornamental Design for a Combined Water Closet Bowl and Foot Rest, of which the following is a specification, reference being had to the accompanying drawing, forming part thereof.

I claim:

The ornamental design for a combined water closet bowl and foot rest, as shown.

PERRY F. STROMBLAD.
